10 Claims.

(Cl. 220—3)

The present invention relates to improvements in high-pressure vessels.

Pressure vessels are usually constructed with a thick, compact wall, that is, a wall which consists of a single, compact body of metal which is of such dimensions that it can withstand the stresses produced by the internal pressure. When very high pressures and, in particular, when vessels of a large diameter are used, difficulties are encountered in making walls of sufficient thickness because tedious and expensive machines are required to work the material and give it uniform quality. In such walls, however, the constructional material is poorly utilized because the pressure load applied to it is unequally distributed. The outer parts of the wall are thus exposed to comparatively little stress.

In the case of closed vessels of cylindrical shape, the wall has to take up not only tangential and radial stresses but also axial stresses. Since the axial stress at the utmost is only half as great as the tangential stresses, the wall of the vessel could be made with half the thickness to receive the axial load, a jacket of suitable strength being shrunk on to take up the tangential stresses. This construction has the advantage that the outer jacket can be more strongly loaded and that smaller blocks may be used in the construction thereof. These advantages are rendered futile, however, by the very great difficulty encountered in the working of the blocks and can only be made fully effective when many layers of small wall thickness are applied.

Attempts have already been made to make high pressure jackets from single layers of sheet metal which are fitted over a thin core tube and welded in longitudinal and round joints. The numerous welded joints, however, are intricate and expensive to prepare and moreover do not ensure with certainty the uniform distribution of the stresses. Furthermore in the construction of such vessels undesirable hollow spaces are formed between the single layers which, when using the vessel, hinder the equalization of temperature in the walls. This is especially true when a flow of heat takes place through the walls because then temperature differences are set up which may lead to excess thermal stresses.

Attempts have also been made to render high pressure flasks more pressure-resistant by winding on wires, but this expedient proved to be unsuccessful and unsuitable for high pressure vessels of high capacity. It has also been proposed to increase the strength of gun barrels by wound intermediate layers, profiled bands having been suggested in order to interlock the windings so as to render them capable of taking up the longitudinal forces. In so doing the bands of every two consecutive layers are arranged in staggered relation with one another in axial direction. In this case, too, no practical solution was reached

and no application of this construction to high pressure vessels has been made either, although these proposals have been known for more than half a century.

The reason for the failure of the art to adapt said known proposals lies in the fact that the shape of the profiles chosen only allows the bands to be interlocked in the axial direction while the bands are prevented from fitting smoothly over one another and their support. The shape chosen renders the bands much too rigid and, moreover, the bands cannot be prepared with the requisite accuracy so that displacements and prominences are inevitable during winding which hinder the attainment of a closed binding and of a smoothly fitting structure.

These drawbacks are avoided by the present invention, the essence of which will be explained by the following detailed description taken in conjunction with the accompanying drawings, in which:

Fig. 1 is a longitudinal section through the wall of a vessel constructed in accordance with one embodiment of the invention;

Fig. 2 is a longitudinal section through the wall of a vessel constructed in accordance with another embodiment of the invention.

Figs. 3 and 4 are longitudinal sectional views showing means for fastening the lid of the vessel;

Fig. 5 is another longitudinal sectional view showing a special type of flange for fastening the lid.

Referring to the drawings, the wall of the pressure vessel illustrated in Fig. 1 comprises an inner tube *a* with two rolled-on steel band layers *b* and *c*. The main object aimed at is to bring about a smooth and safe laying-on of the steel band. The bands are interlocked only to such an extent in the axial direction as is necessary for taking up the axial strains which amount at the utmost to 50% of the tangential strains.

The steel band which is helically wound onto a comparatively thin-walled inner core or support is provided on its outer side with two or more grooves and on the inner side with the same number of preferably continuous projections, accurately corresponding in shape and position to the grooves; the core tube also may be provided on its outer surface with grooves into which the projections on the first band fit. The grooves must, of course, be arranged helically. Conversely the projections may be on the outer side and the grooves on the inner side of the bands, in which case the core tube is provided with helical projections which fit tightly into the grooves of the first band.

Each layer of the steel band must be axially staggered with respect to the preceding layer so that the adjoining edges of the lower layers of the steel band are covered by subsequent layers. The projections of each layer then lie in

the grooves of the previous layer so that the windings of two consecutive layers are interlocked. If the bands of the consecutive layers are staggered by half the width of the band, as shown in Figure 1, every joint is covered with only one band; if the staggering is one third of the width of the band, each joint is covered by two bands, if the staggering is one-fourth of the width of the band, each joint is covered by three bands and so on. In this way the strength in the axial direction can be increased.

The steel band layers thus prepared are still permeable to gas in spite of their close contact so that it is unnecessary to provide special holes for the escape of gases passing outwardly through the core tube by diffusion.

If it is desired to facilitate this passage of gas, the core tube *a* may be smooth and the first steel band *b* wound directly around which may be provided on the inner side with bulges or grooves as shown in Fig. 2 or alternately the core tube may be provided with projections or grooves and the first steel band be provided with a smooth inner surface. There is then formed between the core tube and the first steel band layer a helical channel which is suitable for the passage of the diffused gas. If no discharge of gases be contemplated, both the core tube and the inner side of the first band layer may be smooth.

In the manufacture of the said pressure vessels, entirely smooth, non-profiled bands may also be used and the necessary profile imparted to them by rolling the steel bands onto the vessel with rollers having an appropriate profile. In this way inaccuracies in the preparation of the profile are entirely excluded.

The winding prepared in this way is distinguished by especially high strength, so that the core tube may have a wall thickness of only a few millimeters and yet the strength obtained is superior to that of the conventional type of vessels made with compact walls of the same thickness.

The flanges may be secured to the ends of the jacket by welding. In order to avoid the drawbacks attending through welding between the jacket and the flange, each individual layer of the winding may be welded, screwed or riveted on to one of the steps of the appropriately stepped flange. This modification is, however, difficult to carry out.

I have found that the flanges may be joined in the simplest and safest manner with the wound jacket by providing them with turned out portions accurately corresponding to the grooves or projections of the band winding and then screwing them on to the ends of the winding of the jacket, while if desired shrinking them on. In this way the axial tensile stresses to be taken up by the flanges may be distributed to all underlying layers by way of the last layer of windings, so that an entirely sufficient and safe union is established for all pressures, without it being necessary to provide a further positively closing connection between the single layers, as for example by riveting, in addition to the toothing already provided. It is advantageous to choose the last layer of band stronger so that without undue weakening of this layer the wound packet can be made exactly round at the ends and the grooves can be turned deeper so that they agree accurately with the turned out portion of the flanges and are deep enough to distribute the forces coming into question.

The said high pressure vessels may also be pro-

vided at the ends with covers by securing the latter with studs which are screwed into the ends of the vessel jacket. It is surprising that screws 1 (see Figure 3) which engage in a jacket consisting of many bands 2 lying side by side and one on the other, should remain secure even at high pressures and high temperatures. Experiments have shown that the studs do not loosen in the slightest in the female thread in the wound jacket when overstrained, but break outside of it, even when using highly alloyed steels.

For greater safety it is preferable to apply strengthening rings to the ends of the jacket. In the modification shown in Figure 3 such a ring 4 is screwed on and shrunk.

Contrasted with the use of flanges which, especially in the case of vessels of large diameter, as for example 1000 millimeters, which have to withstand high pressures, as for example 700 atmospheres, must be very heavy, the modification according to Figure 3 has the advantage that the high pressure vessel is considerably lighter and cheaper.

It is possible, however, to combine the two systems of securing the cover, in that in cases where the use of flanges cannot be dispensed with, especially in the case of thin-walled vessels, studs are screwed into the front side in such manner that they project partly into the material of the flange 4 and partly into the material of the winding 2 (see Figure 4).

In cases in which the thickness of the wall is not sufficient for the said method of securing with screwed bolts, and therefore the flanges cannot be dispensed with, the closure of the high pressure vessel is advantageously effected by winding on to the ends of the wound jacket a flange also consisting of steel bands in the manner described and the studs for securing the cover into the winding consisting of flange and jacket. This arrangement may be seen in Figure 5; 2 is the jacket of the high pressure vessel, 5 is the flange wound on in the same way as the jacket and 1 is a screwed bolt. With this arrangement it is possible to dispense entirely with the expensive compact flanges which are difficult to provide. It is preferable to rim the whole flange, or at least its upper and lower ends, by means of a smooth and not too thick shrinkage ring 3. The flange may then be of even thickness throughout (see Figure 5) or tapered in the usual way from the ends of the jacket towards the middle of the jacket.

What I claim is:

1. A high pressure vessel comprising a core tube, steel bands wound thereon in staggered relationship so that each band overlies the joint between the winding of the band beneath to form a plurality of helical layers, each band being provided with at least two projections on one surface and the same number of grooves of the same size and shape on the opposite surface, the projections of each band fitting tightly into the grooves of the adjoining band whereby said helical layers are interlocked and impart axial resistance to the vessel without welding the bands.

2. A high pressure vessel comprising a core tube having a plain exterior surface, a steel band helically wound and shrunk on the exterior surface of said tube at least two projections running the length of said band on the surface of said band opposite to that in contact with the core tube, additional steel bands wound in staggered relationship around said first band, each of said

additional bands having at least two grooves on its inner surface and at least two projections of the same size and shape on its outer surface, the projections of each band fitting tightly into the grooves of the overlying band, whereby the several helical bands are interlocked and impart axial resistance to the vessel without welding the bands.

3. A high pressure vessel comprising a core tube having helical projections thereon, a steel band wound on said tube, said band having grooves of the same size and shape as said projections on said tube, the band being wound so that said helical projections fit tightly into the grooves of said band at least two projections on the surface of said band opposite to that provided with the grooves, these projections corresponding as to number, size, shape and position with said grooves, additional similar steel bands wound in staggered relationship around said first band the projections on the outer side of each band fitting tightly into the grooves on the inner surface of the overlying band, thereby providing a plurality of mutually staggered helical layers, each of which is interlocked with the adjoining element and imparts axial resistance to the vessel without welding the bands.

4. A high pressure vessel comprising a core tube having helical grooves on its outer surface, a steel band wound on said tube, said band having projections of the same size and shape as said grooves, the band being so wound that the projections thereon fit tightly into said helical grooves at least two grooves on the surface of said band opposite to that provided with the projections, additional similar steel bands wound in staggered relationship around said first band, the projections on the inner side of each band fitting tightly into the grooves on the outer side of the underlying band thereby providing a plurality of mutually staggered helical layers, each of which is interlocked with the adjoining element and imparts axial resistance to the vessel without welding the bands.

5. A high pressure vessel comprising a core tube, steel bands wound thereon in staggered relationship so that each band overlies the joint between the winding of the band beneath to form a plurality of helical layers, each band being provided with at least two projections on one surface and the same number of grooves of the same size and shape on the opposite surface, the projections of each band fitting tightly into the grooves of the adjoining band whereby said helical layers are interlocked and impart axial resistance to the vessel without welding the bands, annular flanges arranged near the ends of the vessel, helical grooves on the inner surface of said flanges whereby the flanges may be screwed to the ends of the wound bands and a cover removably attached to each end of said vessel.

6. A high pressure vessel comprising a core tube having a plain exterior surface, a steel band helically wound and shrunk on the exterior surface of said tube at least two projections running the length of said band on the surface of said band opposite to that in contact with the core tube, additional steel bands wound in staggered relationship around said first band, each of said additional bands having at least two grooves on its inner surface and at least two projections of the same size and shape on its outer surface, the projections of each band fitting tightly into the grooves of the overlying band, whereby the several helical bands are interlocked and impart

axial resistance to the vessel without welding the bands, annular flanges arranged near the ends of the vessel, helical grooves on the inner surface of said flanges whereby the flanges may be screwed to the ends of the wound bands and a cover removably attached to each end of said vessel.

7. A high pressure vessel comprising a core tube having helical projections thereon, a steel band wound on said tube, said band having grooves of the same size and shape as said projections on said tube, the band being wound so that said helical projections fit tightly into the grooves of said band at least two projections on the surface of said band opposite to that provided with the grooves, these projections corresponding as to number, size, shape and position with said grooves, additional similar steel bands wound in staggered relationship around said first band the projections on the outer side of each band fitting tightly into the grooves of the inner surface of the overlying band, thereby providing a plurality of mutually staggered helical layers, each of which is interlocked with the adjoining element and imparts axial resistance to the vessel without welding the bands, annular flanges arranged near the ends of the vessel, helical grooves on the inner surface of said flanges whereby the flanges may be screwed to the ends of the wound bands and a cover removably attached to each end of said vessel.

8. A high pressure vessel comprising a core tube having helical grooves on its outer surface, a steel band wound on said tube, said band having projections of the same size and shape as said grooves, the band being so wound that the projections thereon fit tightly into said helical grooves, at least two grooves on the surface of said band opposite to that provided with the projections, additional similar steel bands wound in staggered relationship around said first band, the projections on the inner side of each band fitting tightly into the grooves on the outer side of the underlying band thereby providing a plurality of mutually staggered helical layers, each of which is interlocked with the adjoining element and imparts axial resistance to the vessel without welding the bands, annular flanges arranged near the ends of the vessel, helical grooves on the inner surface of said flanges whereby the flanges may be screwed to the ends of the wound bands and a cover removably attached to each end of said vessel.

9. A high pressure vessel comprising a core tube, steel bands wound thereon in staggered relationship so that each band overlies the joint between the winding of the band beneath to form a plurality of helical layers, each band being provided with at least two projections on one surface and the same number of grooves of the same size and shape on the opposite surface, the projections of each band fitting tightly into the grooves of the adjoining band whereby said helical layers are interlocked and impart axial resistance to the vessel without welding the bands, covers for the ends of said vessel and studs screwed into holes tapped in the ends of the windings for holding the covers in place.

10. The apparatus as defined in claim 9 having rings applied to the ends of the wound bands to strengthen the bands and hold the ends of the bands in position.
